UNITED STATES PATENT OFFICE.

ELTON W. SMITH, OF SEATTLE, WASHINGTON.

RAILROAD SPIKE.

1,407,893.

Specification of Letters Patent. Patented Feb. 28, 1922.

Application filed April 26, 1921. Serial No. 464,604.

To all whom it may concern:

Be it known that ELTON W. SMITH, a citizen of the United States, and residing at Seattle, in the county of King and State of Washington, has invented certain new and useful Improvements in Railroad Spikes, of which the following is a specification.

This invention relates to an improvement in railroad spikes and particularly to a spike 10 constructed of two independent parts, one of which forms the spike proper and the other a means for securing the spike proper against accidental loosening.

The invention contemplates the provision 15 of a locking member arranged to cooperate with the spike proper and in the application of such locking member force the spike proper to cause a portion thereof to be driven into the material of the tie, the locking member, when in fully operative position, cooperating with the spike proper, so as to interlock therewith to prevent accidental separation of the spike proper and locking member.

25 In the drawings:—

Fig. 1 is a perspective view showing the spike and interlocking member in spaced relation.

Fig. 2 is a vertical sectional view partly 30 in elevation illustrating the cooperating application of the improved spike and locking member.

The improved spike is made up of two members, a spike proper 1 and a locking member 2. The spike proper is of the usual dimensions having the driving point 3 and head 4. Below the head the spike is formed on one side with a projection 5 having an outer inclined surface which merges into 35 the surface of the spike at the lower end of said projection. The upper edge of the projection presents an abrupt surface 6 at substantially right angles to the spike surface.

That surface of the spike proper opposite 45 the projection 5 is formed immediately below the head with a recess 7. The cooperating or locking member 2 is of substantially similar form to that of an ordinary spike, though of less dimensions, the inner surface 8 50 of the locking member being plane throughout its length, except at its upper portion, while the outer surface of the locking member is tapered at the lower end at 9 to form a point. The locking member has a head 55 10, the inner margin of which is in the form of a projection 11 adapted to cooperate with the recess 7 in the spike proper, the inter-

locking member immediately below the projection being recessed as at 12 to avoid interference in applying the interlocking 60 member.

The rail 13 is designed to be supported on a usual bed plate 14 which immediately beyond the edges of the rail base is formed with spike receiving openings 15. These 65 openings are substantially equal in that dimension transversely of the rail to the combined width of the spike proper and interlocking member.

Initially the spike proper is passed through 70 the elongated opening 15 and into the tie 16, the movement being continued until the head of the spike proper rests upon the upper surface of the rail base. The proportions are such that in this position, the projection 5 of the spike proper is below the upper surface of the tie. The locking member 2 is then driven into the opening and forces the upper end of the spike proper 75 into intimate contact with the remote edge 80 of the opening 15, at the same time forcing the projection 5 laterally into the material of the tie. The interlocking member is driven into a position which will permit the projection 11 thereof to ride into the 85 recess 7 of the spike proper, at which time the spike proper and interlocking member will so completely fill the opening 15 in the plate that accidental separation of the parts is practically impossible. The plane surface 90 8 of the interlocking member bears squarely against the adjacent surface of the spike proper, thus tending to move the spike proper bodily and to align it vertically with respect to the rail. The projection 5 of the 95 spike proper has been of course forced laterally into the material of the tie, thus forming a recess for itself in the material of the tie, which will materially assist in preventing accidental upward movement of the 100 spike proper.

I claim—

A railroad spike comprising a spike proper having a lateral projection and an engaging member adapted to be driven lengthwise the 105 spike proper to force the projection of the spike proper into the material of the tie, the spike proper being formed with a recess and the engaging member having a projection to seat in said recess when the parts are in co- 110 operative relation.

In testimony whereof I affix my signature.

ELTON W. SMITH.
